UNITED STATES PATENT OFFICE.

JOHN ALLEN HEANY, OF WASHINGTON, DISTRICT OF COLUMBIA.

SELF-STARTING INTERNAL-COMBUSTION ENGINE.

1,141,632.

Specification of Letters Patent.

Patented June 1, 1915.

Application filed April 29, 1912. Serial No. 693,883.

To all whom it may concern:

Be it known that I, JOHN ALLEN HEANY, a citizen of the United States, and a resident of Washington, in the District of Columbia, have invented certain new and useful Improvements in Self-Starting Internal-Combustion Engines, of which the following is a full and clear specification, reference being had to the accompanying drawings, in 10 which—

Figure 1 is a side elevation broken away; and Fig. 2 is a vertical section.

The object of this invention is to so construct the starting mechanism that it shall 15 be built into the engine proper, thereby doing away with the unsightliness, unreliability, lack of durability, and liability to derangement which are necessarily incident to those starting mechanisms which are 20 mere attachments to an engine.

I have illustrated my invention as applied to a well known type of engine (a four cycle twin-cylinder engine) but it will be understood that the invention is applicable, with 25 modifications as to details, to other types of engines.

This invention has special relation to the type of self-starting engine covered by my copending application, Serial No. 688,634.

30 In the drawings, *a* designates the usual working pistons, *b* the working cylinders, *c* the pitmen connecting the pistons to the main crank-shaft *d*, all constructed in substantially the usual manner. Each piston 35 is extended toward the crank-shaft and provided with a supplemental piston *e* larger in diameter than the main piston and working in a supplemental cylinder *f* formed as a continuation of the main cylinder.

40 Entering each supplemental cylinder *f* at its upper end is a port *g* and controlling this port is a valve *h* which opens outwardly with respect to the cylinder and is normally held closed to form a check valve by means 45 of a suitable spring *i*. The stem of this valve depends into the crank case and is provided with a head *j* which slides in a guide way in the upper part of the crank casing. The lower end of this head *j* depends into 50 the crank casing far enough to come into the path of a cam *l* affixed to a cam-shaft *m* which is rotated by gears *n* operated from the main crank shaft. There is one of these 55 cams *l* for each valve, and adjacent to each cam *l* is an annular part *o*. This cam shaft is mounted so as to be capable of a limited

endwise movement, and this movement is imparted to the shaft through a rock shaft *p*, a gear *q* on the same and a cylindrical rack *r* on the cam shaft. The rock shaft *p* 60 is provided with an arm *t* which is connected by a rod *u* to a pivoted lever *v*, which lever is adapted to be operated by a push rod *w*. Preferably, the lever *t* with its connected parts is normally pulled to the right 65 by a spring *x*. With this construction the operator may by simply pressing his foot on the push rod *w* throw the cam shaft into active position, that is, into the position shown in Fig. 1, in which position the cams *l* 70 will be in position to lift the valve stems.

In the engine shown in my drawings, there are four cylinders and the pistons are adapted to work in pairs, as usual in this type of engine. With this type of engine the 75 four cams will be so arranged on their shaft that the valves connected with one pair of the cylinders will be opened while the two valves for the other pair will be permitted to remain closed.

Above the valves *h* the four valve chambers are connected together by a pipe *y*, which pipe is connected to one port of a valve casing *z*, the other port of this valve casing being connected by an extension or 80 prolongation of the pipe *y* to an air storage tank *a'*. In the valve casing *z* is a rotatable valve plug *b'* which is provided with a single transverse port. This valve plug *b'* is attached to and forms the pivotal support of 85 the aforesaid lever *v*, and the port in this plug is so placed that when the push rod *w* is pressed down to bring the cams into active position, said port will connect the two branches of the pipe *y*.

95 It will be observed that when the parts are in the position shown in Fig. 1 the compressed air in the tank will be permitted to enter the two supplemental cylinders whose valves *h* are for the time being held open 100 by the cams *l*, the cams being so arranged that the valves will be held open while the supplemental pistons are at the upper ends of their stroke or are moving downwardly. This air under pressure will force the supplemental pistons downwardly and thus 105 start the engine. When these two supplemental pistons reach the lower extremity of their stroke their cylinders will exhaust through the exhaust port *c'*, shown in Fig. 110 2, and approximately simultaneously therewith the cams will open the other pair of

2

valves *h* and thus permit the compressed air to enter the other pair of supplemental cylinders, whose pistons are then at the upper extremity of their stroke. 5 In this way the engine may be readily started whenever there is sufficient air in the tank.

After the engine is running on its own power, the operator releases the push rod *w* whereupon the spring port causes the valve 10 plug *b'* to close and the cam shaft to shift to the right far enough to take the cams *l* out of the way of the valve stems. The supplemental pistons and cylinders will then immediately commence to operate as pumps, 15 taking the air in through the exhaust port *c* and forcing it past the valves *h* (these valves being now free to act simply as check valves) and on into the tank *a'*, a by-pass *d'* around the valve *b'* being provided, this by- 20 pass being provided with a check valve *e'* opening toward the tank. The pumping operation ceases as soon as the pressure in the tank is brought up to the degree determined upon in building the engine, this degree of 25 pressure being dependent on the capacity of the supplemental cylinders and the amount of clearance *f'* arranged for at the upper ends of the cylinders. As soon as the maximum pressure is obtained and the pumping 30 into the tank stops, then the air entrapped in each one of the supplemental cylinders at every stroke will be alternately compressed to tank pressure and then expanded to atmospheric pressure, thus providing for an 35 ideal cushioning effect in each supplemental cylinder.

It will be observed that with this type of engine it is possible to do away entirely with the valve *b'* and the by-pass *d'* so that the 40 tank will have an unobstructed passage at all times to the spaces above the check valves *h*. In this case the operator in shifting the cam shaft to operative position would be compelled to open two of the valves *h* 45 against tank pressure, whereas in an apparatus in which the valve *b'* and the by-pass *d'* are employed the parts may be so proportioned that the operation of opening the valves *h* in starting the engine will be accomplished 50 before the port in plug *b'* opens, thus rendering it easier to open these valves *h*.

Having thus described my invention, what I claim as new and desire to secure by Letters Patent, is—

1. In combination with a multiple cylinder explosive engine having enlarged supplemental pistons and cylinders, a port entering the upper end of each of the supplemental cylinders, valves controlling these ports and means operated from the engine

shaft for opening these valves, means for rendering the valve operating means inoperative during the pumping action and while the engine is running under its own power, 65 said supplemental cylinders each being provided with an exhaust port at the end opposite the aforesaid inlet port.

2. In combination with a multiple explosive engine, having enlarged supplemental pistons and cylinders, each supplemental cylinder being provided with inlet and exhaust ports, an air reservoir and conduits connecting it to the inlets, valves for these inlets opening toward the air reservoir 75 and means operated from the engine for opening said valves, a valve in the conduit connecting the reservoir to the aforesaid inlets, and means for simultaneously opening said valve and shifting the inlet valve 80 actuating mechanism into operative position.

3. In combination with a multiple-cylinder explosive engine, having enlarged supplemental pistons and cylinders, each supplemental cylinder being provided with inlet and exhaust ports, an air reservoir and conduits connecting it to the inlets, valves for said inlets, and means operated from the engine for opening said valves, a valve in 90 the conduit connecting the reservoir to the aforesaid inlets, and means for simultaneously opening said valve and shifting the inlet valve-actuating mechanism into operative position, said inlet valves adapted to act as 95 check valves when the valve-actuating mechanism is in inoperative position to permit the supplemental pistons to pump air into the reservoir.

4. In combination with a multiple-cylinder explosive engine, having air-compressing means associated with each cylinder, each air-compressing means being provided with inlet and exhaust ports, an air reservoir and conduits connecting it to the inlets, valves for said inlets, and means operated from the engine for opening said valves, a valve in the conduit connecting the reservoir to the aforesaid inlets, and means for simultaneously opening said valve and 105 shifting the inlet valve mechanism into operative position, said inlet valves adapted to act as check valves when the valve-actuating mechanism is in inoperative position to permit the air-compressing means to pump air 110 into the reservoir.

In testimony whereof I hereunto affix my signature in the presence of two witnesses.

JOHN ALLEN HEANY.
